UNITED STATES PATENT OFFICE.

WILLIAM W. HAWKINS, OF BROOKLYN, NEW YORK, ASSIGNOR TO WEBSTER ELECTRIC COMPANY, OF RACINE, WISCONSIN, A CORPORATION OF WISCONSIN.

INDUCTOR MAGNETO.

Application filed January 6, 1922. Serial No. 527,448.

To all whom it may concern:

Be it known that I, WILLIAM W. HAWKINS, a citizen of the United States, and resident of Brooklyn, in the county of Kings and State of New York, have invented a certain new and useful Improvement in Inductor Magnetos, of which the following is a full, clear, concise, and exact description, reference being had to the accompanying drawings, forming a part of this specification.

My invention relates to an inductor magneto and more particularly to an oscillating inductor magneto for ignition purposes.

The invention contemplates a novel arrangement of generating coil, inductor and core structure pole pieces characterized by the fact that a relatively small movement of the inductor serves to cause a complete reversal of flux through the generating coil.

An important feature of my invention is the creation of comparatively little current in the generating winding upon the cocking movement of the rotor and a relatively large current upon the recoil movement of the rotor.

The invention contemplates various improvements in construction and arrangement of various parts which go to make up a simplified, efficient and generally improved ignition magneto of the oscillating inductor type.

In the accompanying drawings illustrating my invention:

Figure 1 is a vertical sectional view of the magneto of my invention, this view being taken on the line 1-1 of Figure 2;

Figure 2 is a horizontal sectional view taken on the line 2-2 of Figure 1, the top wall of the magneto frame or housing being broken away;

Figure 3 is a diagram illustrating the rotor in normal or "recoil" position;

Figure 4 is a similar view illustrating the rotor in "cocked" position;

Figure 5 is a similar view illustrating the rotor in one of the intermediate positions through which it moves under recoil; and

Figure 6 is an elevation of the rotor shaft and the inductor carried thereby.

Similar characters of reference refer to similar parts throughout the several views.

Referring first to Figures 1 and 2, reference numeral 10 indicates a permanent

magnet provided with oppositely disposed laminated pole pieces 11 and 12. A frame or housing 13 of non-magnetic material is preferably cast in contact with the pole pieces, said frame or housing being provided with side openings closed by removable side plates 14-14.

The pole pieces 11 and 12 are substantially F-shaped, but are reversely arranged, the projection *a* of each pole piece, however, lying in a horizontal plane coincident with the axis of the rotor presently to be described. The projection *b* of pole piece 11 lies above said plane and a corresponding projection of pole piece 12 lies below said plane.

The side plates 14-14 are provided with outwardly projecting hollow bosses 15-15 and disposed in said bosses are bearing bushing 16-16. It will be noted that each of said bearing bushings extends inwardly a substantial distance beyond the inner face of the side plate by which it is carried. The purpose of this arrangement will presently appear.

Mounted in bearing bushings 16-16 is the rotor shaft 17 upon which is fixed an inductor 18. Inductor 18 consists of a group of soft iron laminæ forced upon or otherwise secured to the rotor shaft. The inductor laminæ are preferably riveted between side plates 18^a-18^a.

I now call attention to the suitably wrapped generating coil 19. The coil extends from pole piece to pole piece and lies between the projections *a* and *b* of each pole piece. Thus a portion of each of the coil turns lies above the rotor axis and a portion of each turn also lies below the rotor axis. The inwardly projecting portions of the bearing bushings 16 hold the coil out of contact with the rotor shaft. One end of the coil (not shown) is grounded to the magneto frame work and the other end of the coil, indicated at 20 is led upwardly through the top wall of the non-magneto frame work 13, as illustrated in Figure 1.

The machine illustrated being an oscillator, the rotor shaft carries a yoke 21, the yoke being suitably keyed to the rotor shaft and being provided with spring posts, as illustrated in Figure 2. Attached to each of these spring posts is a comparatively heavy tension spring 22, the other end of which is attached to a spring post carried by one

of the brackets 23—23. The brackets 23—23 are screwed to the magneto frame work and incidentally serve to clamp the legs of the permanent magnet to the pole pieces. The 5 rotor shaft is furthermore provided with a push finger 24 which is formed integrally with the collar 25, said collar being keyed or otherwise fixed to the rotor shaft.

It will be understood that in the normal 10 operation of the magneto, the push finger 24 is periodically engaged by a push rod or other engine driven actuator (not shown), moved against the tension of springs 24—24 and released, the springs thereupon snapping 15 the rotor rapidly toward its normal position.

The diagram of Figure 3 illustrates the rotor in its normal position, and Figure 4 illustrates the rotor in its "cocked" position. 20 It will be noted that movement of the rotor from one to the other of the two positions mentioned causes a complete reversal of flux through the generating coil, the direction of flux flow through the inductor, however, being the same in both positions. A current 25 is created in coil 19 whenever the inductor moves from its cocked position to its normal position, or vice versa. The wave created during the cocking movement of the rotor 30 of the present machine is found to be comparatively small. However, the wave created during the recoil movement of the rotor is found to be comparatively large. This is a desirable arrangement because it is only 35 the wave created on the recoil movement of the inductor that is utilized for ignition purposes. The wave created on the cocking movement being comparatively small, the utilized wave builds up to a higher peak 40 than would be possible if the wave produced on the cocking movement were a very large one.

It will be unnecessary to illustrate the circuit connections and auxiliary apparatus 45 which is utilized in connection with my improved magneto, as various combinations in which my magneto may be employed for ignition purposes will be apparent to persons skilled in the art to which my invention relates.

Having thus illustrated and described one embodiment of my invention, I do not limit myself to the specific construction and arrangement of parts herein shown and described, but wish to avail myself of all other 55 embodiments of the invention defined by the appended claims.

What I claim is new and desire to secure by Letters Patent of the United States is:

1. An inductor magneto comprising a 60 magnet, a pair of oppositely disposed pole pieces in contact with the poles of said magnet, each pole piece being of F shape and having a long polar projection and a short polar projection, an inductor rotatably 65 mounted between said pole pieces, said inductor having two diametrically opposite arms, recoil spring mechanism normally holding said inductor with said arms in a horizontal plane, the short polar projections 70 of said F shaped pole pieces lying in a horizontal plane coincident with the ends of said inductor arms when the latter are in their normal positions, said pole pieces being reversely arranged whereby the long polar 75 projections are disposed respectively above and below this horizontal plane, and a generating coil extending from pole piece to pole piece and lying between said polar projections. 80

2. An inductor magneto comprising a magnet, a pair of oppositely disposed pole pieces in contact with the poles of the magneto, each pole piece being of F shape and having a long polar projection, and a short 85 polar projection, an inductor rotatably mounted between said pole pieces, said inductor having two diametrically opposite arms, recoil spring mechanism normally holding said inductor with said arms in 90 a horizontal plane, said pole pieces being reversely arranged with the short polar projections in a horizontal plane coincident with the ends of said inductor arms and with the long polar projections disposed respectively above and below this horizontal plane, the face of each long polar projection being displaced less than 90 degrees from the face of the corresponding short polar 95 projection, a generating coil extending from pole piece to pole piece and lying between the polar projections of each pole piece, side plates wherein said inductor is mounted and bushings projecting inwardly from said side plates, said bushings being adapted to hold the diagonal end portions of said generating coil out of engagement with the inductor. 100

In witness whereof, I hereunto subscribe my name this 21 day of December, 1921.

WM. W. HAWKINS.

Witnesses:

B. TRUBENBACK,
EMILE BOURGEOIS.
